UNITED STATES PATENT OFFICE

163,869

SUNGLASS

George R. Hinman, Sands Point, N. Y., assignor to
Pioneer Scientific Corporation, New York, N. Y.,
a corporation of New York

Application March 1, 1951, Serial No. 14,345

Term of patent 14 years

(Cl. D57—1)

To all whom it may concern:

Be it known that I, George R. Hinman, a citizen of the United States, residing at Sands Point, in the county of Nassau, State of New York, have invented a new, original, and ornamental Design for Sunglass, of which the following is a specification, reference being had to the accompanying drawing, forming a part hereof.

Fig. 1 is a top view of a sunglass, showing my new design;

Fig. 2 is a front elevational view thereof, and
Fig. 3 is a side elevational view thereof.

I claim:

The ornamental design for a sunglass, substantially as shown.

GEORGE R. HINMAN.
